UNITED STATES PATENT OFFICE.

IRVING W. KNIGHT, OF CRANSTON, RHODE ISLAND, ASSIGNOR TO GENERAL FIRE EXTINGUISHER COMPANY, OF PROVIDENCE, RHODE ISLAND, A CORPORATION OF DELAWARE.

AUTOMATIC SPRINKLER SYSTEM.

Application filed December 9, 1924. Serial No. 754,847.

This invention relates to improvements in automatic sprinkler systems. More especially it relates to any dry pipe system having a booster pump between its supply main and its distributing pipes; and particularly the invention relates to means for automatically starting the pump, as the need requires and thereafter maintaining its action. These so-called booster systems provide for sprinkler protection in localities where the available supply pressure is or may be inadequate for effective sprinkler discharge, and are especially useful when the building itself is too weak to support the necessary large supply tank, and when a pump must be available to boost or build up the low water pressure for supplying the sprinklers when a fire occurs. For starting booster pumps automatically it has been proposed to employ an actuating device which responds to a drop in the system pressure, such as follows the opening of a sprinkler. But as the pressure generated by the pump would promptly restore the pressure, some special device is needed in addition, to insure the continuous action of the pump.

The present invention provides actuating apparatus which, for starting the pump, is responsive to a pressure rise, rather than fall, so that the increase of pressure resulting from the pump's action will act upon the actuating apparatus to maintain the pump in operation. It is a feature of the invention that, being responsive only to rise of pressure, it can be arranged in atmosphere with no pressure normally exerted upon it.

An embodiment of the invention is illustrated in the accompanying drawings in which a circuit closer of a type responsive to rise in pressure, is connected with the intermediate chamber of a dry pipe valve. As illustrated this is a differential valve; but the action is such that it might be applied to any type of dry pipe valve having a chamber into which the water flows, or in which the pressure rises, when the valve opens, any such chamber being herein for convenience referred to under the comprehensive term of "intermediate chamber." In the illustrated case the chamber is open to atmosphere through a vent of a type well known which becomes closed when the valve opens. Such opening of the valve occurs upon the giving way of a sprinkler head, with consequent bleeding of air pressure

from the dry pipes. The flow of water which follows, into the intermediate chamber, produces a rise of pressure therein, which is transmitted to the circuit closer and effects the starting of the pump. The further rise of water pressure which follows only adds to the pressure in the closer mechanism and maintains its status, in position for keeping the pump operating.

It is intended that the patent shall cover, by suitable expression in the appended claims, whatever features of patentable novelty exist in the invention disclosed.

In the drawings the single figure is an elevation of a dry pipe system with booster pump and apparatus controlling the same, with the electrical circuits shown somewhat diagrammatically.

Referring to the drawings, water normally stands at whatever pressure may occur in the supply main 10 which is assumed to be too low or uncertain for reliance, and is at the same pressure in the booster pump 12, and riser 14 up to the water clapper 16 of a differential dry pipe valve 18, the pump being still. Beyond the air clapper 20 and dry pipe valve the distributing pipes 22 are filled with air under pressure sufficient to hold the valve closed. Sprinkler heads 24 of which the single one shown is representative, are distributed about the risk, each having a thermally responsive element adapted to give way upon rise of temperature to a predetermined point and thus to permit the head to open for discharge. As the air escapes through the open head, its pressure in the pipes falls until it lets the water pressure unseat the dry pipe valve. The clapper 16 lifts and water flows into the intermediate chamber of the valve, closing the usual vent 26 therefrom and passes through branch piping 28 to a circuit closer 30 which is responsive to pressure rise to start the pump. In the particular arrangement indicated by diagram the water pressure closes the switch 32 and thus makes the circuit from battery 34 through the field winding of a solenoid 36, whose energization draws its armature upward and makes a contact between the terminals 38 of a circuit S controlling the rheostat starter 40 which governs a power circuit 44 for operation of pump motor 42. The pump draws the water from the main 10 and forces it onward at the boosted pressure into the riser 14 and dis-

tributing pipes 22 beyond. This incidentally increases the pressure on the circuit closure 30, but the result is only to maintain the switch 32 closed the more firmly, so that the 5 armature of solenoid 36 is kept in place across the terminals 38. The current therefore continues to flow through the motor, and the pump will keep on supplying pressure until the rheostat shall be released manually, 10 the system drained and reset as initially.

I claim:

1. A sprinkler system having in combination a dry pipe valve, a pump for boosting the water pressure, and means connected 15 with the intermediate chamber of said valve and responsive to rise of pressure therein, for effecting actuation of the pump upon occurrence of said rise of pressure.

2. A sprinkler system having a dry pipe 20 valve with intermediate chamber; a power driven booster pump between the water supply and said valve, adapted to increase the pressure of the system; control means for the power driving the pump; and means responsive to increase of pressure in said in- 25

termediate chamber for actuating said control means to position for driving the pump, thereby automatically to maintain the pump in operation under influence of the pressure it creates. 30

3. A sprinkler system having a dry pipe valve with intermediate chamber; a booster pump adapted to increase the pressure of said system; a motor for driving said pump; a power circuit for the motor; a rheostat 35 controlling said power circuit; another circuit governing the operation of said rheostat; an electromotive device for changing said rheostat governing circuit, comprising an energizing circuit; a circuit closer for 40 said energizing circuit and a pressure controlled device connected with the intermediate chamber of the dry pipe valve and adapted upon rise of pressure therein to change the position of said circuit closer, 45 whereby operation of said pump is effected.

Signed at Providence, Rhode Island, this 17th day of October, 1924.

IRA W. KNIGHT.
